181,156

TEXTILE FABRIC OR SIMILAR ARTICLE

William G. Levin, Peekskill, N. Y.

Application October 22, 1956, Serial No. 43,442

Term of patent 14 years

(Cl. D92—1)

Fig. 1 is a plan view of a textile fabric or similar article, showing my new design; and

Fig. 2 is an enlarged view of the dotted rectangular area shown in Fig. 1.

The design is repeated in a vertical direction.

I claim:

The ornamental design for a textile fabric or similar article, as shown and described.
